(57) **CLAIM**

The ornamental design for a monitor mount, substantially as shown and described.

DESCRIPTION

FIG. 1 is a perspective view of a monitor mount, showing our new design;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second side view thereof.

The broken lines depict portions of the monitor mount that form no part of the claimed design.
